UNITED STATES PATENT OFFICE

2,390,729

TEXTILE TWISTING MACHINE

Gustaf Eugen Nordstrom, Gardner, Mass., assignor to American Fibre Corporation, Gardner, Mass., a corporation of Massachusetts

Application June 2, 1944, Serial No. 538,351

12 Claims. (Cl. 57—54)

This invention pertains to textile twisting machines and is herein illustrated by way of specific example, but without limitation, as embodied in a machine for making paper twine, and relates more especially to improved means for supporting the spool or other package core in such a way as to facilitate doffing the filled spool or core and the donning of an empty spool or core.

In a twisting machine of the Brownell type, which in basic principle, at least, is illustrated in the patent to Brownell, No. 581,672, April 27, 1897, a suitable frame supports a series of like twisting units, each comprising a non-rotating spindle on which is mounted a tubular winding core, for example the barrel of a spool, the lower heads of all of the spools at one side of the machine resting upon a vertically reciprocating traverse rail which causes all the spools at one side of the machine simultaneously to rise and fall, thereby to distribute the twisted material along the spool barrel. Usually the rail is provided with friction material which is operative to resist rotation of the spool to a desired degree. Each winding unit also includes a die, coaxial with the spindle, through which the paper ribbon passes and by means of which it is condensed; a twisting head which receives the condensed strip of paper and which comprises stretching drums about which the strip passes and is tensioned, and a rotary flyer having a delivery eye which revolves about the spindle axis. In the modern machines each unit is driven by its own individual electric motor. Heretofore, the operation of doffing and donning the package has involved considerable difficulty and loss of production.

The principal object of the present invention is to provide improved means for supporting the winding package so that when the package is full it may readily be doffed without stopping the machine as a whole or in any way interfering with the operation of adjacent spindles. A further object is to provide package supporting means so devised that the heavy filled spool or core may be doffed safely and without danger of accidentally dropping it, regardless of the position of the spool-supporting rail. A further object is to provide doffing means which may be actuated by the foot of the operator so as to leave both his hands free for manipulating the winding strand and for removing the filled spool and donning an empty spool or core. A further object is to provide spool-supporting means which is positively locked in operative position except when purposely released by the operator. Other and further objects and advantages of the inven-

tion will be pointed out in the following more detailed description, and by reference to the accompanying drawings wherein

Fig. 1 is a fragmentary elevation illustrating one unit of the twisting and winding mechanism of a machine of the class described;

Fig. 2 is a section on the line 2—2 of Fig. 1;

Fig. 3 is a fragmentary side elevation, partly in vertical section, of one of the winding units of the mechanism showing the spool in operative position, the spool-traversing rail being at the lowermost limit of its traverse;

Fig. 4 is a view similar to Fig. 3 but showing the position of the parts in readiness for doffing or donning the package;

Fig. 5 is a fragmentary vertical section, to larger scale, illustrating details of the spindle support—the parts being in the position of Fig. 3;

Fig. 6 is a view similar to Fig. 5 but showing the parts in the position of Fig. 4;

Fig. 7 is a fragmentary vertical section, generally similar to Fig. 5, showing a modified construction of spindle support; and

Fig. 8 is a similar view showing a modified form of spindle and means for positioning the upper end of the spindle.

Referring to the drawings, the numeral 1 designates generally and more or less diagrammatically a single winding unit or head of a multiple unit twisting machine having a frame comprising uprights 2 and stationary, horizontal connecting rails 3 and 4. Each unit also comprises a die 5 which receives the ribbon 6 of material, for instance paper which is to be twisted, and which folds and compacts this ribbon on its way to the twisting mechanism. The twisting mechanism is, in general, of conventional type such as that disclosed, for example, in the Brownell patent above referred to, including a train of gears 7 supported by a bracket 8 mounted on the frame, one of the upper gears being keyed to a vertical shaft 9, turning in fixed bearings. As in modern machines of this type, the train of gears of each unit receives its motion from an individual drive motor, not shown. The winding unit also comprises the hub 10 (keyed to one of the lower gears of the train) which turns in a fixed bearing 8a carried by bracket 8, the hub 10 carrying the gear housing 11 which protects a set of gears (as in the Brownell patent above referred to) which operate the stretching drums 13. A rotary flyer head 14 is keyed to shaft 9 which turns freely within the gear housing 11. This flyer head 14 has one or more hollow strand delivery arms 15 which revolve about a normally

stationary, package-supporting spindle 17. The flyer head 14 is furnished with a socket which receives the upper end 16 of this spindle, while the lower end of the spindle is carried by a support 18 (Figs. 5 and 6) which, in accordance with the present invention, is mounted to swing from front to rear about a transverse pivot 19 whose axis preferably intersects the axis of the flyer, the pin 19 being mounted at its opposite ends in downwardly directed ears forming parts of a bracket 20 which is rigidly secured to the lower rail 4 of the machine frame. The support 18 is provided with an elongate bearing bore for the lower part of the spindle 17 and within which the spindle may slide axially to an extent sufficient to disengage its upper end 16 from the socket in the head 14. A coiled spring 22 (Fig. 5) seated in the lower end of the bearing bore in the support 18 normally supports the spindle 17 in operative position, and opposes its downward movement. As illustrated in Fig. 6, the lower end of the spindle 17 is bifurcated to provide spaced arms 23 which are connected at their lower ends by a transverse pin 24 constituting a spindle-actuating abutment, and which, as here shown, is provided with an anti-friction roll 25. At the location of this abutment pin 24, the support 18 is provided with a transverse slot 26 for the accommodation of one arm 27 of a lever pivoted on a pin 28 fixed in the swinging support 18, the arm 27 overlying the anti-friction roll 25 of the abutment 24. The forward face of the support 18 is preferably slotted, as shown at 18^x (Fig. 2) so as to accommodate the lever just referred to, the opposite ends of the pin 28 being fixed in the substance of the support 18 at opposite sides of this slot. The aforesaid lever also has the forwardly directed arm 29 which extends outwardly beyond the slot 18^x in the support, and whose under surface 30 is of arcuate curvature constituting a cam.

A bracket 31 is rigidly secured to the bottom rail 4 of the frame, projecting forwardly from the latter and having spaced, parallel, vertical arms 32 and 33 (Fig. 1) providing guideways for a vertically movable slide 34. (Figs. 5 and 6). At its rear side this slide is provided with a latch element 35 which, in the normally operative position of the parts, as shown in Fig. 5, engages substantially flat and vertical surfaces 36 of the support 18, thus normally retaining the support positively in its operative position with the spindle 17 vertically disposed. The slide 34 is provided with a forwardly directed pin 37 which is received in an elongate slit in one arm 38 of a treadle lever (Fig. 1) mounted to swing in a vertical plane about a pivot pin 39 projecting forwardly from a lateral ear 40 carried by the guide member 32. The opposite arm of this lever is shaped to provide a treadle 41 which may be engaged by the foot of the operator, thereby to swing the lever and thus to raise the pin 37 and move the slide 34 and the latch 35 upwardly. When the latch is thus elevated, as shown in Fig. 6, it disengages the surfaces 36 of the support 18, so as to permit the support to be swung forwardly to the position shown in Figure 6. In this position the spindle 17 is inclined forwardly so that, as shown in Fig. 4, it is out of the field of revolution of the arms of the flyer. In this position the winding core or spool may readily be doffed or donned.

The slide 34 is also provided with a pair of parallel downwardly directed arms 42 (Fig. 1), whose lower ends are connected by a transverse

pin 43 on which is mounted a cam-follower roll 44 which engages the cam surface 30 of the lever arm 29. This cam surface is so contoured that when the slide 34 is raised from the normal position of Fig. 5 to the doffing position of Fig. 6, the engagement of the roll 44 with this cam surface swings the lever arm 29 about its pivot pin 43, thereby also swinging the arm 27 downwardly and forcing the spindle 17 downwardly in opposition to the spring 22 to an extent sufficient to disengage the upper end of the spindle from the socket 16. When the spindle has thus been disengaged from the socket, the support 18 may be freely swung forwardly by the operator so as to place the parts in the doffing and donning position of Fig. 4.

As is customary in machines of this type, there is provided a vertically reciprocating traverse rail 45 having a friction element, for example a pad 46 of leather or the like, upon which the lower head 47 of the spool 48 rests during the winding operation, this friction pad retarding the rotation of the spool so as in cooperation with the rotation of the flyer to wind the strand of material on the barrel of the spool. While a spool having two heads is customarily employed, the invention is not in any way limited to the type of package core employed, and instead of a spool having two heads, a spool having a single head may be used, or, in fact, any other customary type of tubular package core.

Since the wound package may be of large dimensions and very heavy, it is desirable to prevent this package from dropping any substantial distance when the support 18 is swung to the doffing position. If, for example, the traverse rail 45 were near the upper limit of its travel when the support 18 was swung forwardly, the spool might drop a substantial distance unless caught by the operator, and thus might cause damage either to the spool head or to the mechanism for controlling the spindle support. To avoid this possibility, it is preferred to provide the traverse rail with a bracket 49 corresponding to each winding unit—each bracket having a forwardly directed arm 50 disposed in a plane slightly below that of the friction pad 46 so as not to contact the winding spool during normal operations, but so as to underlie the spool when the spindle support is moved forwardly, and to limit downward movement of the spool relatively to the spindle when the support is swung forwardly, regardless of the position of the traverse rail 45.

With the arrangement just above described, all that is necessary for the operator to do, when the package is to be doffed, is to place his foot on the treadle 41, whereupon the latch 35 is retracted, the spindle is moved down to disengage its upper end from its socket, and the support 18 is swung forwardly so as to place the package in the doffing position. The operator then removes the package from the spindle, places a fresh winding core on the spindle, and pushes the spindle back to its operative position and secures the end of the strand to the spool barrel. As the spindle resumes its normal vertical position, the spring 22 raises it to insert its upper end 16 in the socket in head 14, thus releasing the latch 35 and permitting it to drop down into its normal position, as shown in Fig. 5, whereupon the parts are in readiness for the resumption of the winding operation.

Since the spool turns relatively to the spindle, it may, under some circumstances, be desirable

to facilitate the turning of the spindle freely so as to reduce the friction between it and the spool. Thus, as illustrated in Fig. 7, the lower end of the spindle 51 is reduced in diameter, as shown at 53, and disposed within the inner face of an anti-friction ball bearing, the outer race of which is an inverted cup-shaped member 53 arranged to slide in the elongate bearing bore in the support 18, the cup-shaped member having a screw-threaded retaining ring 54 for holding the bearing in place. The lower part of this cup-shaped member is slotted to provide spaced arms 55 between which is arranged the anti-friction abutment roll 25 which is engaged by the lever arm 27 in the same way as above described—spring 22 engaging the lower ends of the arms 55 and thus normally holding the spindle in operative position although permitting it to be moved downwardly to disengage its upper end from the socket. With this arrangement, the lower end of the spindle turns freely in the ball bearing, and thus the spindle may turn at a rate approximating that of the spool, thus reducing friction.

In Fig. 8 a further modification is illustrated wherein the spindle is reduced in diameter at its upper portion, as shown at 56, this portion of smaller diameter terminating at a shoulder 57 and being embraced by a freely turning sleeve 58 whose upper end bears against a flange 59 forming part of a plug having a pin which is fixed in a socket in the upper end of the spindle, the plug comprising a pintle member 60 which engages the inner race of a ball bearing 61 secured in a socket in the flyer head 14 by means of a retainer ring 62. The lower part of the spindle is mounted in the support 18 in the same way as illustrated in Fig. 5, for example. Provision is thus made for reduction of friction between the upper end of the sleeve 58 and the flyer head 14.

While certain desirable embodiments of the invention have herein been illustrated by way of example, it is to be understood that the invention is not necessarily limited to these precise embodiments but is to be regarded as broadly inclusive of any and all modifications falling within the terms of the appended claims.

I claim:

1. A twisting machine of the kind in which the strand material is twisted and wound by a flyer upon a tubular support to form a package, and wherein the tubular support is arranged to turn on a normally fixed spindle and is moved axially of the spindle, thereby to distribute the strand material and wherein the upper end of the spindle is normally held in a socket coaxial with the flyer, characterized in having a support for the lower end of the spindle, said support being mounted to swing about an axis transverse of the spindle, a latch normally operative positively to prevent swinging of the support, the support having therein a bearing in which the spindle may move axially, spring means opposing downward movement of the spindle, and a single manually actuatable element operative concomitantly to withdraw the latch, thereby to permit the support to be swung, and to move the spindle downwardly thereby to disengage its upper end from the socket.

2. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which

the package core is rotatable and having means providing a socket for the upper end of the spindle and a support for the lower end of the spindle, characterized in that the spindle support has an elongate bearing for the spindle, resilient means opposing downward motion of the spindle in said bearing, and means for moving the spindle downwardly in said bearing, said latter means comprising a pin projecting from the spindle, a lever having an arm overlying the pin, a vertically movable part having a pin underlying the opposite end of the lever, and manually actuatable means for moving said vertically movable part.

3. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which the package core is rotatable and having means providing a socket for the upper end of the spindle and a support for the lower end of the spindle, characterized in that the spindle support is pivoted to swing forwardly about an axis intersecting the axis of the flyer and has an elongate bearing for the lower part of the spindle, spring means opposing downward movement of the spindle in said bearing a lever pivotally mounted upon the support to swing about an axis parallel to that of the support, the spindle having an abutment element with which one arm of the lever engages, the opposite arm of the lever being shaped to constitute a cam, a vertically movable slide, and an abutment carried by the slide engaging the cam arm of the lever, and means for moving the slide so as to swing said lever and thereby to move the spindle downwardly.
4. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which the package core is rotatable and having means providing a socket for the upper end of the spindle and a support for the lower end of the spindle, characterized in that the spindle support is pivoted to swing forwardly about a transverse axis below the lower end of the spindle, the support having an elongate bearing in which the spindle may move downwardly from normal position sufficiently to disengage its upper end from the socket, spring means opposing such downward movement, locking means normally operative to prevent forward movement of the support, and means including a single actuating lever, operative to move the locking means from operative position and to move the spindle downwardly so as to disengage its upper end from the socket thereby to permit the support to swing forwardly.
5. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which the package core is rotatable and having means providing a socket for the upper end of the spindle and a support for the lower end of the spindle, characterized in that the spindle support is

pivoted to swing forwardly about a transverse axis below the lower end of the spindle, the support having bearing means for the spindle so constructed and arranged that the spindle may move downwardly from normal position sufficiently to disengage its upper end from the socket, spring means opposing such downward movement, a latch normally operative to prevent forward movement of the support, and means, including a single actuating lever, operative to retract the latch from operative position and to move the spindle downwardly so as to disengage its upper end from the socket.

6. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which the package core is rotatable and having means providing a socket for the upper end of the spindle and a support for the lower end of the spindle, characterized in that the spindle support is pivoted to swing forwardly about a transverse axis below the lower end of the spindle, the support having an elongate bearing in which the spindle may move downwardly from normal position sufficiently to disengage its upper end from the socket, spring means opposing such downward movement, a latch normally operative to prevent forward movement of the support, and means, including a single actuating lever, operative to move the spindle downwardly to disengage its upper end from the socket and to release the latch thereby permitting the support to be swung forwardly so as to move the end of the spindle out of the field of action of the flyer.

7. A twisting machine of the class described comprising a plurality of independently driven twisting and winding units each designed to twist strand material and to wind the twisted material upon a hollow core to form a package, and each unit including a rotary flyer and a normally stationary spindle coaxial with the flyer upon which the package core is rotatable and having means providing a socket for the upper end of the spindle and a support for the lower end of the spindle, characterized in that the spindle support is pivoted to swing forwardly about a transverse axis below the lower end of the spindle, the support having an elongate bearing in which the spindle may move downwardly from normal position sufficiently to disengage its upper end from the socket, spring means opposing such downward movement, a latch normally operative to prevent forward movement of the support, and actuating means including a latch-carrying slide, a manually operable lever for moving the slide, a cam follower carried by the slide, a lever pivotally mounted on the support and having an arm which is engaged by the cam follower, a lever having a second arm, and an abutment carried by the spindle which is engaged by said latter arm of the lever, the parts being so constructed and arranged that operation of the manually actuated lever moves the slide to retract the latch from operative position and moves the spindle downwardly to release its upper end from the socket.

8. A twisting machine of the class described comprising a plurality of independently driven twisting and winding units each designed to twist strand material and to wind the twisted material upon a hollow core to form a package, and

each unit including a rotary flyer and a normally stationary spindle coaxial with the flyer upon which the package core is rotatable and having means providing a socket for the upper end of the spindle and a support for the lower end of the spindle, characterized in that the spindle support is pivoted to swing forwardly about a transverse axis below the lower end of the spindle, the support having an elongate bearing in which the spindle may move downwardly from normal position sufficiently to disengage its upper end from the socket, spring means opposing such downward movement, a latch normally operative to prevent forward movement of the support, and actuating means including a movable latch carrier, a treadle lever provided with a foot treadle, and means connecting the treadle lever to the latch carrier whereby movement of the treadle lever in one direction moves the latch to inoperative position, and means, connected to the latch carrier so as to be actuated by the latter, operative to move the spindle downwardly.

9. A twisting machine of the kind in which the strand material is first twisted and then wound by a flyer upon a spool to form a package, and wherein the spool is arranged to turn on a normally fixed spindle and is supported by a vertically reciprocating traverse rail so as to be moved axially of the spindle thereby to distribute the winding strand material, the upper end of the spindle being normally held in a socket coaxial with the flyer and wherein the flyer turns in fixed bearings, characterized in having supporting means for the lower end of the spindle so constructed and arranged that the spindle may be moved axially downward to disengage its upper end from the socket, means normally opposing such downward movement of the spindle, and means carried by the traverse rail operative to prevent the package from dropping when the support is swung forwardly.

10. A twisting machine of the kind in which the strand material is first twisted and then wound by a flyer upon a spool to form a package, and wherein the spool is arranged to turn on a normally fixed spindle and is supported by a vertically reciprocating traverse rail so as to be moved axially of the spindle thereby to distribute the winding strand material, the upper end of the spindle being normally held in a socket coaxial with the flyer and wherein the flyer turns in fixed bearings, characterized in having supporting means for the lower end of the spindle so constructed and arranged that the spindle may be moved axially downward to disengage its upper end from the socket, means normally opposing such downward movement of the spindle, and a shelf projecting forwardly from the traverse rail and disposed in a plane below the operative surface of the traverse rail, said shelf being designed to prevent downward movement of the package regardless of the position of the rail when the support is swung forwardly.

11. A twisting machine of the kind in which the strand material is first twisted and then wound by a flyer upon a tubular core or spool to form a package, and wherein the core or spool is arranged to turn on a normally fixed spindle and is moved axially of the spindle by a vertically reciprocating traverse rail thereby to distribute the winding strand material, and wherein the upper end of the spindle is normally held in a socket coaxial with the flyer, characterized in that the flyer turns in fixed bearings and in having yieldable supporting means for the

lower end of the spindle so constructed and arranged that the spindle may be moved downwardly, thereby to disengage its upper end from the socket, the lower end of the spindle being bifurcated to provide spaced legs, a transverse pin extending from one leg to the other, and a spindle-depressing lever having an arm which overlies said pin.

12. A twisting machine of the kind in which the strand material is first twisted and then wound by a flyer upon a tubular core or spool to form a package, and wherein the core or spool is arranged to turn on a normally fixed spindle and is moved axially of the spindle by a vertically reciprocating traverse rail thereby to dis- 10 15

tribute the winding strand material, and wherein the upper end of the spindle is normally held in a socket coaxial with the flyer, characterized in that the flyer turns in fixed bearings and in having yieldable supporting means for the lower end of the spindle so constructed and arranged that the spindle may be moved downwardly, thereby to disengage its upper end from the socket, the lower end of the spindle having therein an axially extending slot, a transverse pin extending across said slot and fixed to the spindle, an anti-friction roll turning freely on said pin, and a spindle-depressing lever having an arm which contacts said roll.

GUSTAF EUGEN NORDSTROM.
